Primary Examiner — Karen S Acker*Assistant Examiner* — Wendy Arminio(74) *Attorney, Agent, or Firm* — Preston P. Frischknecht; Project CIP(57) **CLAIM**

The ornamental design for a mattress cover with pattern, as shown and described.

DESCRIPTION

FIG. 1 is a perspective view of the mattress cover with pattern shown in a position of use within a bedding environment drawn in broken lines; and,

FIG. 2 is an enlarged top view of the mattress cover with pattern.

The broken lines in FIG. 1 showing a bed frame depict environmental structure and form no part of the claimed design. The dot-dash-dot broken lines in the figures depict the boundaries of the claimed design and form no part thereof. All other broken lines depict portions of the mattress cover with pattern that form no part of the claimed design.
